DITCH DRAINING DEVICE
Hubert L. Elliott, Aline, Okla.
Filed Jan. 14, 1963, Ser. No. 251,112
7 Claims. (Cl. 103—87)

This is a continuation-in-part of application Serial No. 166,063, filed January 15, 1962, now abandoned.

The present invention generally relates to pump units, and more particularly to a pump unit specifically designed for use in pipeline construction for the removal of water and debris from the narrow excavated ditches within which the pipes are normally laid.

In the laying of pipelines there is frequently a substantial lapse of time between the excavation of the ditch and the laying of the pipe therein, this lapse of time allowing the ditch to become filled with water and debris such as sand, mud and rocks, these materials being of a highly abrasive nature thus tending to result in a substantial amount of wear to conventional excavating equipment normally used to remove the water and debris.

It is a primary object of the present invention to provide a ditch draining device particularly intended to operate in a manner resulting in an effective excavation of both water and various types of debris, including sand, mud, rocks and trash, while at the same time greatly reducing the amount of wear which might be expected from the highly abrasive nature of the material involved.

In accomplishing the above object, it is contemplated that an impeller-type pump be utilized, the impeller operating at a maximum speed of 600 r.p.m., both the impeller and the power source therefor being mounted entirely within a narrow rigid framework, this framework being of a width so as to allow for its lowering into the trench to be excavated.

Likewise, it is an object of the present invention to provide a pumping unit which, while relatively simple in construction, is capable of efficient operation over extended periods of time.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a front elevational view of the ditch draining device comprising the present invention;

FIGURE 2 is a side elevational view of the device;

FIGURE 3 is an enlarged sectional view of the impeller drive means;

FIGURE 4 is an enlarged cross-sectional view taken through the impeller assembly;

FIGURE 5 is a cross-sectional view taken substantially on a plane passing along line 5—5 in FIGURE 4; and

FIGURE 6 is a perspective view of one of the impeller blades.

Referring now more particularly to the drawings, reference numeral 10 generally designates the portable pumping unit comprising the present invention, this unit or device 10 consisting basically of a framework 12 supporting and completely enclosing an impeller assembly 14 and a power plant 16.

The framework 12 consists of a plurality of elongated rigid rod-like members preferably of hollow tubular form so as to provide the desired stability while maintaining the over-all weight of the device 10 at a minimum. These framework members include two elongated base members 18 provided with upwardly and outwardly sloping ends 20 for facilitating the dragging of the entire unit 10 along the ground if such be deemed necessary. The framework 12 also includes rear, central and forward vertically extending pairs of members 22, 24 and 26, the forward pair

2

of members 26 being substantially shorter and having their upper ends engaged with the forward ends of two longitudinally extending members 28 interconnecting the upper ends of the members 22 and 24 by means of rearwardly inclined members 30. A centrally located pair of horizontal members 32 are also provided, these members extending the full length of the framework 12 and forming a support for the power plant 16 which is mounted directly behind the central vertical pair of members 24. It will also be appreciated that the framework 12 further includes a plurality of transversely extending members 34 as illustrated in FIGURE 1.

As will be appreciated from FIGURES 1 and 2, the framework 12 completely surrounds the impeller assembly 14, the power plant 16 and the drive means interconnecting the power plant and impeller assembly thus affording a substantial degree of protection in the event of a dropping or swinging of the unit against various objects.

The power plant 16, mounted between and above the horizontal members 32, is to preferably be a 22 horsepower diesel engine. With attention now being directed to FIGURE 3, it will be noted that the power plant drive shaft 36 has the outer end thereof rotatably received within the enlarged end 38 of the pinion shaft 40, suitable clutch means, only the drum 42 being illustrated, being provided. The clutch drum 42 is secured to the socket end 38 of the pinion shaft 40 by both a key 44 and setscrew 46, a Zerk fitting 48 also being utilized so as to allow for lubrication. A housing 50 is provided about the pinion shaft 40 and has one end thereof secured to the clutch housing 52 and the other end bolted to the gear case 54 within which the bevel pinion gear 56 engages and drives the enlarged beveled ring gear 58.

The driven gear 58 is rigidly affixed to the upper end 35 of the impeller shaft 60 which extends vertically through a housing 62 secured by bolt means 64 to the bottom of the gear case 54, this housing 62 being sealed at the upper and lower ends thereof so as to retain lubricating oil 66 therein. The upper sealing means for the housing 62 40 is generally referred to by reference numeral 68 while the lower sealing means is generally referred to by reference numeral 70 and consists specifically of a snap ring 72, set collar 74, rotary seal garlock 76, seal 78 and retainer 80. A bronze bearing 82 is also provided about 45 the impeller shaft 60 above the seal means 70.

The impeller assembly 14, rigidly affixed to the lower end of the impeller shaft 60, consists of upper and lower plates 84 and 86 having vertically aligned centrally located intake openings 88 and 90 therein. These plates 50 84 and 86 are maintained in spaced relationship by three substantially radially extending impeller blades 92, these blades 92 being slightly arcuate with the outer portions thereof being substantially rectangular, the upper and lower edges 94 extending in a horizontal plane to a point 55 designated by reference numeral 96 at which the upper and lower edges converge arcuately toward each other as at 98. As will be appreciated from FIGURES 4 and 5, the points 96 correspond to the circumference of the intake openings 88 and 90 thus facilitating free passage 60 of the water and debris into the impeller. The water and debris upon entering through the intake openings 88 and 90 is laterally deflected into the path of the blades 92 by a centrally located circular baffle plate 100 of slightly greater diameter than the aforementioned intake 65 openings 88 and 90. It will be noted that the impeller blades 92 include elongated slots 102 extending inwardly from the inner edges thereof, these slots 102 receiving the baffle plate 100 for the mounting of the blades 92 thereon, these blades 92 being rigidly affixed, as by welding, to 70 the upper and lower plates 84 and 86 as well as the baffle plate 100 thus forming an integral impeller unit.

The impeller unit is mounted within a cylindrical hous-

ing 104, this housing 104 being of a size so as to provide for only a minimum clearance between the outer edges of the blades 92 and the side wall 106 of the housing, this clearance being on the order of $\frac{1}{8}$ th inch and being consistent completely about the periphery of the housing 104. In other words, the wall 106 of the casing or housing 104 is concentric with the impeller.

Two oppositely directed discharge openings 108 are provided through the housing wall 106. A discharge passage 110 is provided in communication with each discharge opening 108 and consists of a first straight, flat side wall 112 extending tangentially to the cylindrical housing 104 at one side of the corresponding opening 108 and a second straight side wall extending from the housing 104 at the other end of the discharge opening 108 parallel to said first straight side, this second side being referred to by reference numeral 114. These passages 110 communicate at their outer ends with vertically extending pipes 116 which in turn communicate with an enlarged discharge header 118 positioned above and forward of the impeller assembly 14 for connection to a suitable discharge hose or other means for disposing of the excavated material.

Turning again to the impeller housing 104 as seen in FIGURES 4 and 5, it will be noted that this housing includes a bottom wall 120 having a central aperture 124 therein corresponding to the intake opening 90 so as to allow for the entering of water and debris, this bottom wall 120 also forming the bottom wall for the passages 110. The top wall 126 is also provided with an aperture 128 therethrough similar to the aperture 124 and positioned in alignment with the intake opening 88 thus allowing for the introduction of water, dirt and debris through both the top and bottom of the housing. This top wall 126 consists of a circular member having a diameter larger than the diameter of the housing 104 and being releasably bolted thereto by bolts 130 extending through the top wall 126 at peripherally spaced points and through a top plate 132 integrally formed with the housing and passage walls, the entire impeller assembly 14 being rigidly secured to the enlarged lower end of the impeller shaft housing 62 by support arms 134 welded to both the housing 62 and the top wall 126, the support arms 134 being outwardly arched so as to avoid any interference with the intake of water and debris into the impeller assembly 14.

With continuing reference to FIGURES 4 and 5, it will be noted that three blades 92 are provided, the blades 92 and discharge openings 108 being so related as to insure that the radial chambers formed between adjoining blades 92 are at no time out of communication with either one or the other of the discharge openings 108. For example, it will be noted that as the blade A passes beyond the juncture between the wall 114 and the housing side 106, the blade B has already passed the juncture between the wall 112 and the side wall 106 of the housing. This is deemed highly significant in that by such an arrangement the water introduced into the impeller is allowed to expand evenly with no water or debris being trapped within a chamber so as to require the carrying or pushing of stationary or "dead water." Also of significance is the provision of only a minimum amount of clearance between the impeller blades and the casing thus enabling a much more positive displacement of the water and debris as the blades rotate. The greatly improved discharge resulting from the use of a minimum clearance, on the order of $\frac{1}{8}$ th of an inch completely about the periphery of the housing 104, in conjunction with the use of three blades 92 related to the discharge opening 108 in such a manner so as to insure that the radial chambers are at all times in communication with one or the other of the discharge opening enables the operation of the impeller at relatively low speeds with the maximum necessary speed being approximately 600 r.p.m., this slow speed greatly reducing the amount of

wear which would normally result from the highly abrasive nature of the materials being discharged.

Referring again to the over-all device 10 as best seen in FIGURES 1 and 2, it will be noted that a transverse lifting plate 134 is rigidly affixed to the frame work 12 and includes an opening 136 therein within which a lifting means, such as a crane, is releasably engaged for lifting and moving the entire device 10, both the impeller assembly 14 and power plant 16 being effectively protected against injury by the surrounding framework 12 in the event that the device 10 is accidentally released.

From the foregoing, it will be readily apparent that a novel ditch pumping unit has been defined, this unit including an impeller type assembly which, while of generally simple construction, is believed to constitute a significant advance in the art. The assembly consisting basically of three impeller blades rotating within a concentric cylindrical housing having two oppositely directed discharge openings with the blades and discharge openings being related in such a manner so as to insure that the radial chambers formed by the blades are at all times in communication with at least one of the openings, another significant feature residing in the provision of only a minimum clearance, for example, on the order of $\frac{1}{8}$ th inch, between the blades and the housing wall so as to insure a positive displacement of all of the water and debris introduced into the impeller. Because of this particular arrangement and the efficiency of the impeller assembly resulting therefrom it is contemplated that this impeller be run at slow speeds of no more than 600 r.p.m., this resulting in a substantial reduction in the wear resulting from the highly abrasive nature of the discharged material heretofore normally encountered in such operations.

In operation, the device is lowered into a ditch with the impeller assembly being submersed into the material to be discharged, this material, consisting of water, sand, mud, stones and other debris, entering into the housing through the upper and lower intake openings and subsequently being deflected outward by the centrally located baffle plate for discharge through the discharge openings by the impeller blades, the discharged material subsequently exiting through the discharge pipe and discharge header. The sucking of the water into the impeller chamber and the subsequent discharge of the water therefrom is effected in a smooth and continuous flow without interruption of flow normally encountered by the necessity of moving trapped water within chambers not in communication with a discharge opening.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A portable pumping unit comprising a vertically orientated impeller assembly, a power plant for said impeller assembly, said power plant being located adjacent said impeller assembly, means operatively connecting said power plant and said impeller assembly, said impeller assembly including a circular housing, a plurality of discharge openings in said housing, an impeller positioned within said housing, a vertically extending shaft on said impeller operatively associated with the power plant for effecting rotation of the impeller, said impeller including a plurality of radially extending blades forming a plurality of radial chambers, said blades being arranged so as to provide for a constant direct communication of each chamber with one or another of the discharge openings, and a framework, said impeller assembly and power plant being mounted within

said framework, said framework completely surrounding said impeller assembly and power plant.

2. The structure of claim 1 wherein said framework is relatively narrow so as to allow for the introduction of the entire unit into narrow ditches, said framework consisting of a plurality of elongated rod-like members, and means rigidly affixed to the uppermost portion of the framework for engagement by an external lifting means whereby movement of the unit is effected.

3. The structure of claim 1 including discharge passages communicating with said discharge openings, each of said passages being formed by a first straight side wall extending tangentially from the circular housing, and a second straight side wall extending from said housing parallel to and spaced from said first side wall, the discharge openings consisting of those portions of the housing between the parallel side walls.

4. The structure of claim 3 wherein said blades are of a length so as to allow for only a minimum clearance between the ends thereof and the surrounding housing throughout the entire circumference of the housing.

5. The structure of claim 4 wherein there are two discharge openings and three impeller blades.

6. The structure of claim 5 wherein the means operatively connecting the power plant and impeller assembly includes a gear reduction unit so as to enable the operation of the impeller at a slow speed.

7. An impeller assembly including a circular housing having side, top and bottom walls, two oppositely directed discharge openings being provided through the side wall, a discharge passage communicating with each discharge opening, each passage consisting of a first straight side extending tangentially from the circular housing at one end of the corresponding discharge opening, and a second straight side extending from the housing at the other end

of the discharge opening parallel to said first straight side, an impeller positioned substantially concentrically within said housing, a vertically extending shaft on said impeller adapted for engagement with a source of power for effecting a rotation of said impeller, said impeller including three radially extending blades forming three radial chambers, the relationship between the width of the discharge openings and the arrangement of the blades being such so as to provide for a constant direct communication of each chamber with one or the other of the discharge openings, said blades being of a length so as to position the outer ends thereof at a substantially constant minimum clearance from the housing side wall between the point of engagement of each of said second straight sides of the discharge passages and the point of tangential engagement of the first straight side of the other discharge passage.
